for Ornamenting Stoves, &c

Patented June 1. 1858.

Des. 1011

George F. Seavey, of Boston Mass.
Letters Patent No 1011, dated June 1, 1858

The schedule referred to in these Letters Patent & making part of the same.

To all persons to whom these presents shall come:

Be it Known that I,

George F. Seavey, of Boston, in the County of Suffolk, and State of Massachusetts, have invented or produced a new ornament in bas-relief, or a design for an ornament for stoves or other articles and I do hereby declare that the same is fully represented in the accompanying drawing.

It is composed of the trefoil, the horns or branches, b, b, the spear-head, c, and the pendant spear head, d, arranged and having the form as exhibited.

I claim the said design or ornament as shown in the drawing.
